DESIGN FOR A CIGARETTE DISPENSER

William C. Panzer, Chicago, Ill., assignor to Russakov Can Company, Chicago, Ill., a corporation of Illinois

Application June 20, 1940, Serial No. 93,136

Term of patent 7 years

To all whom it may concern:

Be it known that I, William C. Panzer, a citizen of the United States, residing in Chicago, Cook County, Illinois, have invented a new, original, and ornamental Design for a Cigarette Dispenser, of which the following is a specification, reference being had to the accompanying drawing, forming a part thereof.

Figure 1 is a plan view of a cigarette dispenser showing my new design; and Figure 2 is an elevational view.

I claim:

The ornamental design for a cigarette dispenser, substantially as shown.
